HUMIDIFIER

Everett D. Betts, Dowagiac, Mich., assignor to
The Rudy Furnace Company, Dowagiac, Mich.

Application February 24, 1934, Serial No. 712,769

9 Claims. (Cl. 126—113)

The main object of this invention is to provide a humidifier well adapted for use in hot air furnaces and the like.

Another object of my invention is to provide a humidifier comprising a water pan of improved construction and having means associated therewith for supporting the same in the top or bonnet of the furnace in a novel manner.

Objects relating to details and economies of my invention will appear from the description to follow. The invention is defined and pointed out in the claims.

A structure which is a preferred embodiment of my invention is illustrated in the accompanying drawings, in which:

Fig. 1 is a fragmentary top plan view of a hot air furnace embodying the features of my invention, a portion of the top of the furnace bonnet being broken away to show the water pan.

Fig. 2 is a fragmentary view in side elevation, a portion of the furnace top being broken away and shown in vertical section.

Fig. 3 is an enlarged detail section of the water pan taken on a line corresponding to line 3—3 of Fig. 1.

Fig. 4 is a fragmentary section on a line corresponding to line 4—4 of Fig. 5.

Fig. 5 is an enlarged fragmentary section on a line corresponding to line 5—5 of Fig. 4.

Fig. 6 is an enlarged perspective view of the hood.

Fig. 7 is a rear elevation of the rear escutcheon and adjustable slide assembly.

In the embodiment of my invention illustrated in the drawings, numeral 1 indicates a hot air furnace having a top or bonnet 2 provided with an inwardly inclined or conical wall 3. The air is heated by the furnace and circulated upwardly through the chamber 4 formed by the bonnet 2 and outwardly through the conduit openings 5, 5 which are conventionally illustrated, the conduits not being illustrated.

I provide the wall 3 of the bonnet with opposed openings surrounded and reinforced by the front and rear escutcheons 6 and 7 respectively. These escutcheons are preferably curved to fit the wall 3 and are secured thereto in any suitable manner as by means of the bolts 8. The front escutcheon is provided with a central opening 9 the lower half of which is adapted to receive the channel-like neck 10 of the relatively shallow water pan 11 disposed within the chamber 4, the bottom of the channel having a flange 30 engaging the front of the escutcheon. The chan-

nel 10 is tiltably supported by the lower edge of the opening 9 of the escutcheon 6.

The channel 10 is covered by means of a hood 12 which loosely fits within the upper half of the central opening in the front escutcheon, the top 13 of the hood being curved downwardly and inwardly to fit the top of the opening through a wide range of inclinations of the front escutcheon (see Fig. 4). My humidifier is thus made readily adaptable to hot air furnaces having bonnets 10 the side walls of which slope at different angles. The hood is removably disposed on the channel 10 and is provided with a flange 14 for coaction with the removable cover 15 of the water inlet or float chamber 16. The water admitted to the float chamber is controlled by the float valve 17 which is conventionally illustrated, the water pipe being shown at 18, Fig. 1. A drain cock is provided at 19 for cleaning the pan.

The rear escutcheon 7 is secured to the wall 3 and is provided with a vertical central opening through which the overflow pipe 20 extends, the inner end of the pipe being connected to the inner end of the pan 11 as shown for supporting the latter. The overflow pipe is supported by the vertically adjustable slide 21 associated with the rear escutcheon 7. The position of the slide is controlled by the screw 22 by means of which the overflow pipe 20 and water pan 11 can be adjusted to their proper level.

The water pan 11 is elongated as shown, the neck 10 extending through the wall 4 being relatively deep and narrow. The neck merges into a central longitudinal concave channel 23 of increasing width and decreasing depth toward the inner end of the pan. The inner end of the pan is semi-circular as shown by Fig. 1. The channel-like neck also merges into a peripheral upwardly sloping ledge 24 of substantially uniform depth and of increasing width toward the inner end of the pan. The overflow outlet is disposed slightly above the bottom of the outer ledge 24 whereby there is provided a body of water having a relatively deep central portion substantially surrounded by a relatively shallow portion, the two providing a large water evaporating surface.

For this reason, my humidifier is of exceptionally large capacity and functions efficiently to supply the warm air circulating through the bonnet 2 with the proper amount of moisture. The relatively deep central channel 23 provides an adequate supply of water at all times while the ledge 24 acts to quickly evaporate the shallow water thereabove. By shutting off the water supply and opening the drain cock 19, the entire

contents of the pan may be drained inasmuch as the drain cock is placed at the lowest point, there being no obstructions in the path of the water thereto. My improved humidifier is extremely simple and economical in its parts and yet it is very effective and efficient for the purpose intended.

I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters Patent is:

1. In a humidifier, the combination with a hot air furnace having a casing wall provided with front and rear openings, of a front escutcheon secured to said wall and having a central opening, a relatively shallow water pan disposed within said wall and having a water supply channel fitting and extending through the lower half of the central opening in said front escutcheon and tiltably supported by the lower portion thereof, a hood covering said channel and loosely fitting within the upper half of the central opening in said front escutcheon, the top of the hood being curved downwardly and inwardly to fit the top of the opening through a wide range of inclinations of said front escutcheon, a rear escutcheon secured to said wall and having a vertical central opening, a combined overflow pipe and support connected to the rear of said water pan and extending through said vertical central opening, and a vertically adjustable slide on said rear escutcheon for supporting said pipe and the pan at their proper level.

2. In a humidifier, the combination with a hot air furnace having a conical upper wall provided with front and rear openings, of a front escutcheon secured to said wall and having a central opening, a relatively shallow water pan disposed within said wall and having a water supply channel fitting and extending through the lower half of the central opening in said front escutcheon and tiltably supported by the lower portion thereof, a hood covering said channel and loosely fitting within the upper half of the central opening in said front escutcheon, the top of the hood being curved downwardly and inwardly to fit the top of the opening through a wide range of inclinations of said front escutcheon, and a combined overflow pipe and support connected to the rear of said water pan and extending through said rear opening.

3. In a humidifier, the combination with a hot air furnace having a wall provided with front and rear openings, of a front escutcheon secured to said wall and having a central opening, a relatively shallow water pan disposed within said wall and having a water supply channel fitting and extending through the lower half of the central opening in said front escutcheon and tiltably supported by the lower portion thereof, a hood covering said channel and loosely fitting within the upper half of the central opening in said front escutcheon, the top of the hood being curved to fit the upper edge of the central opening through the range of inclination of the escutcheon and a combined overflow pipe and support connected to the rear of said water pan and extending through said rear opening.

4. In a humidifier, the combination with a hot

air furnace having a bonnet provided with upwardly and inwardly inclined front and rear walls, of a front escutcheon secured to said front wall and having a central opening, a relatively shallow water pan disposed within said wall and having a water supply channel fitting and supported by the lower portion of the central opening in said front escutcheon, a hood covering said channel and loosely fitting within the upper portion of the central opening in said front escutcheon, the top of the hood being curved downwardly and inwardly to fit the top of the opening through a wide range of inclinations of said front escutcheon, a combined overflow pipe and support connected to the rear of said water pan and extending through said rear wall, and a vertically adjustable means on said rear wall for supporting said pipe and the pan at their proper level.

5. In a humidifier, the combination with a hot air furnace having a bonnet provided with upwardly and inwardly inclined front and rear walls, of a front escutcheon secured to said front wall and having a central opening, a relatively shallow water pan disposed within said wall and having a water supply channel fitting and supported by the lower portion of the central opening in said front escutcheon, a hood covering said channel and loosely fitting within the upper portion of the central opening in said front escutcheon, the top of the hood being curved downwardly and inwardly to fit the top of the opening through a wide range of inclinations of said front escutcheon, and a combined overflow pipe and support connected to the rear of said water pan and extending through said rear wall.

6. In a humidifier, the combination with a hot air furnace having a bonnet provided with upwardly and inwardly inclined front and rear walls, of a front escutcheon secured to said front wall and having a central opening, a relatively shallow water pan disposed within said wall and having a covered water supply channel fitting and extending through the central opening in said front escutcheon and tiltably supported by the lower portion thereof, the cover of the channel being curved to fit the upper edge of the central opening through the range of inclinations of the escutcheon, a combined overflow pipe and support connected to the rear of said water pan and extending through said rear wall, and a vertically adjustable means on said rear wall for supporting said pipe and the pan at their proper level.

7. In a humidifier, the combination with a hot air furnace having a bonnet provided with upwardly and inwardly inclined front and rear walls, of a front escutcheon secured to said front wall and having a central opening, a relatively shallow water pan disposed within said wall and having a covered water supply channel fitting and extending through the central opening in said front escutcheon and tiltably supported by the lower portion thereof, the cover of the channel being curved to fit the upper edge of the central opening through the range of inclinations of the escutcheon, and a combined overflow pipe and support connected to the rear of said water pan and extending through said rear wall.

8. In a humidifier, the combination with a hot air furnace having a conical upper wall provided with a front opening, of a front escutcheon secured to said wall and having a central opening, a relatively shallow water pan disposed within said wall and having a water supply channel fit-

- ting and extending through the lower half of the central opening in said front escutcheon and tiltably supported by the lower portion thereof, and a hood covering said channel and loosely fitting within the upper half of the central opening in said front escutcheon, the top of the hood being curved downwardly and inwardly to fit the top of the opening through a wide range of inclinations of said front escutcheon.
- 5 9. In a humidifier, the combination of a front escutcheon having a central opening, a relatively shallow water pan having a water supply channel fitting and extending through the lower half of the central opening in said front escutcheon and tiltably supported by the lower portion thereof, and a hood covering said channel and loosely fitting within the upper half of the central opening in said front escutcheon, the top of the hood being curved downwardly and inwardly to fit the top of the opening through a wide range of inclinations of said front escutcheon.
